CLAIM

The ornamental design for a display screen or portion thereof with graphical user interface, as shown and described.

DESCRIPTION

FIG. 1 is a front view of a display screen or portion thereof with graphical user interface showing my new design; FIG. 2 is a second embodiment thereof; and, FIG. 3 is a third embodiment thereof.

(Continued)

The broken lines in the drawings illustrate a display screen or portions thereof or environment and form no part of the claimed design.
